UNITED STATES PATENT OFFICE.

WALLACE S. AYRES, OF HAZLETON, PENNSYLVANIA.

COAL CLEANING AND SEPARATING MACHINE.

1,069,517.

Specification of Letters Patent.

Patented Aug. 5, 1913.

Application filed February 24, 1909. Serial No. 479,699.

To all whom it may concern:

Be it known that I, WALLACE S. AYRES, a citizen of the United States, residing at Hazleton, in the county of Luzerne and 5 State of Pennsylvania, have invented certain new and useful Improvements in Coal Cleaning and Separating Machines; and I do hereby declare the following to be a full, clear, and exact description of the invention, 10 such as will enable others skilled in the art to which it appertains to make and use the same.

This invention relates to coal cleaning and separating machines, especially to that class 15 of machines represented in Patent No. 798,385, granted August 29, 1905, to this applicant, and has for an object to provide improved means for separating the coal from the slate and other matter with which 20 it is ordinarily associated.

A further object of the invention is to provide, in a device of this class, a feed-pan and baffle-plates adapted and positioned to spread out any massed pieces of coal and 25 slate as they are moving slidably across the inclined floor of the separator, so that such moving floor will have a better opportunity of action, without interference, upon the pieces of slate.

With these and other objects in view, the 30 invention comprises certain novel constructions, combinations and arrangements of parts, as will be hereinafter more fully described and claimed.

Figure 1 of the drawing forming a part 35 of this application is a top plan of a traveling separating floor with the improved feed-pan and baffle-plate associated therewith. Fig. 2 is a view partly in elevation showing 40 one inclination of the traveling floor and showing in section the feed pan, the section being taken on a line approximately coincident with the left hand edge of the floor as it appears in Fig. 1. Fig. 3 is a view in vertical section showing the opposite inclination of the floor. Fig. 4 shows the feed pan 45 partly in section and partly in elevation, the section being taken on a line immediately adjacent to the outer edge of the pan.

The traveling floor 1 shown in the drawing is disposed with the corner 2 the lowest, the inclination of such floor being greater than the angle of repose of the coal and less than the angle of repose of the slate. Across 50 the traveling floor 1 a guide bar 3 is extended similar to the guide bar 17 shown in

the above mentioned patent, with a feed-pan 4 positioned to discharge coal from the screens or other source upon the surface of the traveling floor 1 and at any desired distance above the guide bar 3 by the location of the bolts 21 and 22, engaging holes 23. 60

The feed-pan 4 is provided with a bottom having several segments presenting a series of increasing inclinations. The illustration 65 shows three segments 17, 18 and 19, and the arrows show the downward directions of their inclinations, although any number of these segments can be provided at will. It is obvious that a large number of segments 70 may be so connected. A number of segments connected as described form a warped surface. The mixture of coal and slate passing down the feed-chute 20 enters upon the feed-pan 4 in the direction shown by the arrow in such chute and is delivered from it in direction parallel to the guide 3. This series of increasing inclinations effects a change of direction in the stream of material fed upon the feed-pan and without the 75 destructive impact that would occur when using but one inclination of the bottom of the feed-pan, and also a comparatively uniform velocity of delivery upon the separating floor. These increasing inclinations of 80 the segments of the bottom also cause the coal, which runs more rapidly than the slate, to tend to crowd the slate to the higher edge 85 of the stream as it enters upon the separating floor. 90

Upon the top of the guide bar 3 a plate 5 is secured, provided with a plurality of openings 6 to any of which may be pivotally secured angle braces 7, such braces comprising a body portion pivoted to the plate 5 95 and an upstanding flange portion 8 against which a bar 9 is disposed and secured in position in any approved manner, as by the pivot bolt 10, which also secures the plate 7 to the plate 5. 100

The brace plate 7 is provided with a segmental slot 11 adapted to engage a pintle 12 in one of the spaced openings 6 of the bar 5, and by means of which the angular position of the brace 7 relative to the plate 5 may 105 be adjusted. The bars 9 are also provided with a plurality of holes or openings 13 by means of which the bars 9 may be adjusted longitudinally relative to the brace plates 7. At their extremities the bars 9 carry baffle- 110 plates comprising a flange secured to the bar 9 by means of pins 15 and with web portions

extending downwardly adjacent to the surface of the traveling floor 1. At the end of the traveling floor 1 opposite the feed-pan 4, means for receiving and conducting the coal, 5 as the tail-apron 16, is provided. The traveling floor is mounted upon suitable rollers 25 and 26, these rollers being journaled at 27 and 28 in bearing blocks 29 and 30. One of these bearing blocks is stationary and 10 the other is slidable in order to provide for adjustment. The blocks are mounted in a suitable frame 31 and the device is supported upon an inclined framework 32 pivoted at 33 upon a base portion 34. The adjusting device 35 provides means for varying the inclination of frame 32.

In the specific construction shown in the drawing, the floor 1 travels in the direction indicated by the arrow, so that being inclined at an angle greater than the angle of repose of coal disposed upon said surface, the coal discharged from the chute 4 has a tendency to travel toward the lowest corner 2 of the floor, irrespective of the 20 movement of the traveling floor 1. The guide 3 is positioned to prevent the separated coal from passing over the lower edge of the traveling floor, so that it normally passes downwardly along the upper edge 25 of the guide bar 3 and is discharged upon the tail-apron 16. As, however, a considerable quantity of pieces of slate and other foreign material are ordinarily associated with the coal, the tendency of certain 30 massed groups of them is to follow the course of travel of the traveling floor 1, and they are thereby deflected from the course sought by the included pieces of coal, viz:—downwardly against the guide 3. 35 Consequently an intermediate path is followed by these massed groups and the baffle-plates 14 are interposed in their path for the purpose of spreading out these groups as the same pass downwardly and impinge 40 upon the upper surface of the baffles, and to separate such coal and slate so that the traveling floor, which is disposed at an angle less than the angle of repose of pieces of slate, may act upon such slate without interference and carry such pieces of slate 45 therewith and dump them over the higher edge of the floor shown at the lower edge of the drawing, it being understood that the floor is traveling in the direction indicated 50 by the arrow.

Different conditions of coal, as to quality, shape of pieces and other conditions, make the adjustment of the baffle-plates necessary or desirable, and several adjustments are 60 provided for. The number of baffle-plates and associated parts shown in the drawing are to be understood as only representative, such number being varied at pleasure, in operation, and the position of the arms 9 in 65 parallelism with the line of travel of the

traveling floor is also representative, it being understood that the angle of such arms can be varied at will, as well as the length of such arms, to secure any desired adjustment of the baffle-plates relative to the floor, 70 to the feed-pan and to the guide bar 3.

What I claim is:—

1. In a device of the class described, a traveling floor, means to discharge material upon the floor and a plurality of independently adjustable baffle plates arranged above 75 the floor.

2. In a device of the class described, a separating floor and a feed pan associated therewith, the bottom of such pan comprising a plurality of plane surfaces inclined in different direction and disposed at different angles each of such surfaces gradually merging into the adjoining surface. 80

3. In a device of the class described, a separating floor and a feed pan associated therewith, the bottom of such pan comprising a plurality of plane surfaces inclined in different directions and disposed at different angles, all of said surfaces discharging 90 transversely of the main line of feed. 85

4. In a device of the class described, a separating floor and a feed pan having a segmental bottom, each adjoining segment thereof having a different downward inclination measured on the line of maximum inclination in its surface, said line of maximum inclination of each successive segment being disposed at an angle with that of the preceding segment, certain of the adjoining 95 segments discharging in the same direction. 100

5. In a device of the class described, a separating floor and a feed pan having a segmental bottom, each adjoining segment thereof having a different downward inclination measured on the line of maximum inclination in its surface, said line of maximum inclination of each succeeding segment being disposed at an angle with that of the preceding segment, certain of the adjoining 105 segments discharging in the same direction, the aforesaid pan constituting a separating and guiding device for the material delivered thereby, and guiding means on the floor coöperating with the device last mentioned. 110

6. In a device of the class described, a traveling floor set at an inclination, means to discharge material upon the floor, a guide bar extending across the floor and positioned to guide the travel of the material, baffle-plates carried by the bar, and means to vary the relation of the baffle plates with reference to the guide bar. 120

7. In a device of the class described, a traveling floor set at an inclination, means to discharge material upon the floor, a guide bar extending across the floor and positioned to guide the travel of the material, baffle-plates carried by the bar, means for 125 130

varying the distance between the baffle plates and the bar, and means for varying the inclination of such plates.

8. In a device of the class described, a traveling floor set at an inclination, means to discharge material upon the floor, a guide bar extending across the floor and positioned to guide the travel of the material, baffle-plates carried by the bar, and means for varying the inclination of each of such plates independently of the others.

9. In a device of the class described, a traveling floor, means to discharge material upon the floor, a guide extending across the floor and positioned to guide the travel of the material, baffle-plates carried by the bar, means for varying the distance between the baffle plates and the bar, and means for varying the inclination of such plates.

10. In a device of the class described, a traveling floor means to discharge material upon the floor, a guide bar extending across the floor and positioned to guide the travel of the material, baffle-plates carried by the bar, and means for varying the inclination of each of such plates independently of the others.

11. In a device of the class described, a traveling floor set at an inclination, means to discharge material upon the floor, a guide bar extending across the floor and positioned to guide the travel of the material, baffle-plates carried by the bar and inclined at an angle thereto, and means to vary the relation of the baffle-plates and the guide bar.

12. In a device of the class described, a traveling inclined floor, means to discharge material upon the floor, means for guiding the material across the floor, devices connected with such means, for spreading the

material passing over the floor and means for varying the angle of such devices individually with reference to the guiding means.

13. In a device of the class described, a traveling floor set at an inclination, means to discharge material upon the floor, a guide bar extending obliquely across the floor and positioned to guide the material, arms carried by the guide bar and extending laterally therefrom, and baffle plates carried by the arms.

14. In a device of the class described, a traveling floor having an inclined surface, means to discharge material upon the floor, a guide bar extending obliquely across the floor and positioned to guide the material, brace plates carried by the guide bar and adjustable relative thereto, arms carried by the brace plates and adjustable relative thereto, and baffle plates carried by the arms.

15. In a device of the class described, a traveling floor disposed at an inclination, means to discharge material upon the surface of the floor, a guide bar extending obliquely across the floor and positioned to engage and direct the travel of the material, a plate secured to the guide bar, a plurality of brace plates pivotally secured to the plate, arms carried by the brace plates and adjustable relative thereto, and baffle-plates carried by the arms adjacent the surface of the floor.

In testimony whereof I affix my signature in presence of two witnesses.
